UNITED STATES PATENT OFFICE.

JOHN Y. BROWN AND JOHN R. BROWNING, OF EVERETTVILLE, WEST VIRGINIA.

BENDING MACHINE.

Application filed June 19, 1926. Serial No. 117,093.

Our invention relates to a machine for bending metal bars and has particular reference to a machine especially designed for use in bending railway rails, either to straighten rails which have previously been 5 bent to curved form, or to bend to curved form rails which are straight.

Our machine is of the type embodying three or more pairs of rollers between which a bar or rail is adapted to be passed either 10 to straighten or to bend same to curved form, and our purpose, generally speaking, is to provide a machine of this type that is simple in construction, strong, durable, relatively cheap and easy to produce and thoroughly 15 reliable and efficient in operation, its particular advantage being that large quantities of bars or rails may be straightened or bent to curved form in a minimum of time and at small expense.

20 More particularly it is our purpose to provide means for yieldably mounting the rollers of our machine, so that in the event foreign matter is carried by a bar or rail between the rollers neither the rollers nor 25 other parts of the machine will be marred or damaged thereby. Also, it is our more particular purpose to provide means for quickly and easily adjusting one of the pairs of rollers with respect to the other pairs of 30 rollers, so that bars or rails may be bent to any desired curve.

With the foregoing and other purposes in view, our invention consists in the novel features of construction, combination and arrangement of parts as will be hereinafter 35 more fully described, illustrated in the accompanying drawings and defined in the appended claim.

In the drawings, wherein like characters 40 of reference denote corresponding parts in the different views:—

Fig. 1 is a side elevation of a bar or rail bending machine embodying the novel features of our invention;

45 Fig. 2, a top plan view of our machine;

Fig. 3, a section on the line 3—3 of Fig.

2; and

Fig. 4, a section on the line 4—4 of Fig. 3.

By reference to the drawings it will be observed that our machine includes essentially 50 a bed plate 10, preferably but not necessarily of elongated, rectangular shape, having rising therefrom, adjacent to one longitudinal edge thereof, a pair of spaced, parallel frame members 12, 12 which frame members may

either be formed integrally with said bed plate as herein shown, or be formed separately therefrom and be secured rigidly thereto in any desired manner. The various elements going to make up our complete machine are mounted on said bed plate and the latter may in turn be mounted on any suitable type of wheeled truck (not shown) whereby the machine as an entirety may conveniently be transported from place to place.

60 The frame members 12, 12 are of webbed construction and in the present instance each of them has formed therein at longitudinally spaced points three vertically extending bearing guide channels 14 all of which open through the tops of their respective frame members and extend downwardly into the latter any desired distance, the two outermost channels of each frame member terminating in this instance at their lower ends a short distance above the upper face of bed plate 10 and the intermediate channels opening at their lower ends into enlarged cut out spaces 16 formed in said 70 frame members.

65 Journalized in suitable bearings 18 at the sides of the frame members 12 is a horizontal shaft 20 which extends transversely with respect to said frame members and is located beneath the intermediate channels 14 within the spaces 16. On this shaft is secured a pair of eccentric disks 22, 22 which, respectively, underlie the lower open ends of the 75 two intermediate channels 14.

70 An upper bearing block 24 and a lower bearing block 26 is mounted in each channel 14, grooves being formed in the sides of said blocks to receive ribs 28 which project into the channels 14 from the walls of the frame 80 members defining said channels whereby said blocks are permitted to slide vertically in said channels, but are held against movement in all other directions.

75 The four lower, outermost blocks 26 rest 100 at their lower ends directly against the bottom walls of the four outermost channels 14 whereby their downward movement is limited, whereas the two lower, intermediate blocks 26 rest at their lower ends upon the 105 eccentric disks 22, 22, respectively, whereby they may be raised or lowered by means of said eccentric disks.

80 The blocks 24 and the blocks 26 obviously are arranged in pairs transversely of the 110 machine, and journaled for rotation in each pair of upper blocks 24 is a horizontal shaft

30, while journaled for rotation in each pair of lower blocks 26 is a horizontal shaft 32, all of said shafts extending transversely across the space between the frame members 12, 12 as is manifest.

Secured to each upper shaft 30, between the frame members 12, 12, is a roller 34, while secured to each lower shaft 32, between said frame members, is a roller 36, three pairs of rollers, each pair including one upper and one lower roller, thus being disposed at spaced points longitudinally of the frame members between the latter.

Bolted or otherwise removably secured over the top of each frame member 12 so as to close the upper ends of the channels 14 is a plate 38, and threaded in each of said plates are three screw members or bolts 40, one in alinement with each channel 14, each 20 either carrying or bearing against a disk 42. A coil spring 44 is arranged between the upper end of each upper bearing block 24 and a related disk 42, these springs serving, as is manifest, to impose downward pressure on the upper bearing blocks 24 and thus hold the upper rollers 34 yieldably in contact with their related lower rollers 36, screw members or bolts 40 providing means whereby the force of said springs may be adjusted.

Each of the shafts 30 and 32 has keyed or otherwise suitably secured thereto a gear wheel 46, the gears of related upper and lower shafts being in mesh with one another and the gears of the lower set of shafts being connected together through the intermediation of idler gears 48 mounted on suitable stub shafts projecting from one of the frame members 12 whereby all of said shafts 30, 32 are caused to rotate in unison, the upper shafts in one direction and the lower shafts in an opposite direction.

Any suitable means may be employed to drive the gears 46, an electric motor 50 mounted on the bed plate 10 and connected with one of the lower outermost gears 46 by means of a train of reduced speed gears 52 being employed in this instance for that purpose.

In order to provide a convenient means of rotatably adjusting the eccentric disks 22, 22 for the purpose of raising or lowering the intermediate pair of rollers a lever 54 is secured to shaft 20 which lever includes a bolt 56 cooperating with a toothed segment 58 suitably secured to the bed plate or to one of the frame members 12 whereby said eccentric disks may be held in any rotatably adjusted position.

If desired, cross members 60 may be bolted 60 across the ends of the frame members 12, 12 to brace and stiffen the latter.

The rollers 34 and 36 as is understood are formed of the proper shape, so that cooperating upper and lower rollers form between them an opening of substantially the same

cross sectional shape as the bars or rails to be bent by the machine, it being further understood, of course, that by removing the plates 38, 38, the bearing blocks with their shafts and rollers may readily be removed 70 from the machine to permit rollers of different shapes to be interchanged so that the machine may be adapted to operate on bars or rails of practically any cross sectional shape. In the present instance the rollers 75 are so shaped that an opening of substantially the same cross sectional shape as a railway rail is formed between each pair of cooperating upper and lower rollers thereby adapting the machine for bending railway 80 rails, and, assuming the motor to be driving the various rollers in the manner aforementioned, the operation of our machine is apparent and as follows: If a rail is to be straightened, lever 54 is swung to rotate the 85 eccentrics 22 to a position in which the intermediate pair of rollers will be held with the rail receiving opening between them in alinement with or in the same horizontal plane as the openings between the other two 90 pairs of rollers. A curved rail to be straightened then is introduced at one end between one of the outermost pairs of rollers and fed between such pair of rollers successively between the other pairs of rollers, 95 emerging from the last pair of rollers between which it passes truly straight due of course to the simultaneous three point contact of the three alined pairs of rollers therewith during its passage through the machine. If, on the other hand, it is desired to bend a straight rail to curved form, the eccentrics 22 are adjusted either to raise or lower the intermediate pair of rollers as may be desired, so that the opening between them 100 will be disposed the proper distance out of line with the openings between the rollers of the two other pairs to impart the desired curve to the rail and the latter then is fed through the machine as before, same emerging bent to a curve due to the simultaneous, 105 three point, disaligned contact of the three sets of rollers therewith. Should any foreign substance of a hard nature be fed with the rollers thereby avoiding damage to the latter.

Sufficient looseness or play is provided between the teeth of the gears 46, 46 and 48 to 110 permit the aforementioned adjustments of the rollers by means of the eccentrics 22, 22, and said teeth are sufficiently deep to maintain the gears at all times in driving engagement with one another.

From the foregoing description considered in connection with the accompanying drawings it is believed that the construction, operation and advantages of our improved machine will be fully understood. We desire 115

to point out, however, that various changes and desirable additions may be made in and to the structural arrangement shown within the spirit and scope of our invention as defined in the appended claim.

We claim:

In a bar or rail bending machine, a pair of spaced frame members, three pairs of bearing blocks carried by each frame member, shafts connecting corresponding blocks of the respective frame members, a roller carried by each shaft, the intermediate pairs of blocks being slidably mounted in said

frame members, a rotatable shaft mounted below said intermediate blocks, eccentric disks on said shaft supporting said intermediate blocks, a lever on said shaft for rotating same, a fixed toothed segment, and means carried by said lever cooperating with said segment to retain said lever in different angularly adjusted positions.

In testimony whereof we hereunto affix our signatures.

JOHN Y. BROWN.

JOHN R. BROWNING.
